UNITED STATES PATENT OFFICE.

ROSSITER S. SCOTT, OF NEW YORK, N. Y.

GARMENT HOLDER.

Application filed April 1, 1925. Serial No. 19,863.

This invention relates to garment holders and involves a detachable fastening means having a wide range of usefulness, for example, for garters, belts, girdles, arm or 5 wrist bands, waiscoat straps and the like.

The general object of the invention is to improve the structure and efficiency of such garment holders and to increase the comfort and service thereof. A particular object is to 10 enable the use of a wide band, flexible or otherwise, with the increased comfort and service thereof, without the need of a wide fastening means, which frequently would be seriously objectionable. This invention provides a combination of a wide band with a 15 narrow fastener, yet one which is adjustable to alter the length of the band, as with other fasteners, clasps and the like. With the present invention a narrow clasp or fastener may be employed with a wide band and without the need of a special woven band, as has heretofore been proposed. Other and further objects and advantages of the invention 20 will be explained in connection with the specific embodiments hereinafter to be described, or will be apparent to those skilled in the subject matter.

To the attainment of such objects and advantages the present invention consists in 25 the novel garment holder, or fastening means or clasp, and the novel features of combination, arrangement, structure and detail herein illustrated or described.

In the accompanying drawings, forming 30 a part hereof, Fig. 1 is a face view of one form of clasp of fastener plate.

Fig. 2 is an exterior or front view of a 35 garment holder, for example a garter, embodying the present invention and using the clasp plate of Fig. 1, this embodiment being 40 specifically adaptable for use as a sock garter.

Fig. 3 is a cross section taken through the 45 garter and fastening pieces of Fig. 2 when the same are in their operative engagement.

Fig. 4 is a similar view, but showing the 50 interior or opposite side of the same, but with the sock attachment omitted, so that this embodiment is adaptable as a simple band or golf garter, or belt or girdle, or arm or wrist band, according to the size and length thereof.

Fig. 5 shows the clasp plate of a modified embodiment as will be described.

Fig. 6 is a longitudinal central cross section 55 of an embodiment employing the clasp plate of Fig. 5.

Fig. 7 shows a clasp plate having features of modification available for any of the other embodiments.

The clasp plate 9 shown in Fig. 1 is provided with a first or outer slot 10, which is narrow at its center, but having enlarged ends 11 to receive the doubled fabric or elastic as will be explained. The slot 10 is arranged along one side of the plate in a direction transverse to the band. At the opposite side of the plate is shown a second band-receiving slot 12. This is shown of different shape from the slot 10 and has longitudinal extensions 13 with inturned slot 70 extremities 14. This arrangement produces a pair of symmetrical or twin lugs 15 which assist in disposing and holding the band.

In this embodiment the fastening stud is intended to engage directly with the plate 75 9, and an enlarged hole 16 to receive the stud is shown, with a narrowed slot 17 extending longitudinally outwardly therefrom. By outwardly is meant in a direction away from the stud fastening at the other end of the 80 band. The stud hole 16 and the inner slot 12 are shown connected by a passage or mouth 18 which serves the purpose of enabling the fabric to project to a greater degree into the hole 16 to act as a guard in 85 preventing the accidental disengagement of the stud from the socket or slot 17; and also serves the purpose of forming a passage of greater area acting with hole 16 in securing an easy manual disengagement of the fastening 90 stud from the plate 9 when desired.

Fig. 2 shows a practical embodiment employing the clasp plate 9 of Fig. 1, for example as a sock garter. Wide elastic bands are very desirable, as they distribute the 95 pressure, give greater comfort, and are more durable. Such a wide band 19 is shown extending between the socket member or clasp plate 9 and the stud member to be described. The wide material of the band is shown bent 100 and curved inwardly at 19^a where it enters the slot 12. The fabric, with its edges folded or doubled in surrounding the twin lugs 15, extends in this condition across the outer side of the plate, as seen in Fig. 2, and thence through the slot 10, the free end 20 of the band or elastic, taking the doubled or in-folded form 20^a adjacent to the slot 11. The extremity of the free portion 20 of the band 105 may be embraced by a suitable binder 21.

The band 19 at the opposite end may be stitched to a suitable pad 22 upon which it 110

is secured, for example by stitches, a stud piece 23 from which projects a stud 24 having a shank and head as seen in Fig. 3. The pad 22 is shown formed with a sock extension 25, having any ordinary sock grip device 26. These elements 25 and 26 however are omitted in the plain band, garter, belt, etc., as seen in Fig. 4, which otherwise is the same as Fig. 2.

10 In applying the garment holder as shown in Figs. 1 to 4, the socket fastener member or clasp plate 9 will be brought around and placed above the stud fastener member at the other end. The enlarged portions 16 of 15 the stud receiving slot will thereupon be pressed down upon the stud, and the parts relatively moved to cause the stud shank to slide into the narrowed slot 17 of the clasp plate. As clearly seen in Fig. 3 the fabric or elastic of the band lies closely adjacent to 20 the front side of the clasp plate, and thereby presses upon the stud head when engaged in the slot. The fabric thus serves to prevent the accidental sliding and detachment of the 25 stud. The fabric indeed may be slightly pushed or pulled into the stud hole 16, as indicated at 27 in Fig. 4, to form an effective guard for the described purpose.

It will be seen that the described structure 30 permits a relatively narrow clasp plate 9 in connection with a wide fabric band 19. At the same time the fabric is nicely and conveniently disposed, so that the front view of the assembled article forms a slightly and 35 attractive combination, as seen in Fig. 2. The clasp plate can be made almost half the width of the band used, thus enabling a very wide band to be worn with a comparatively small garment holder and adjustment clasp combination.

The purpose of the extensions 13 and 40 45 50 55 60 65 70 75 80 85 90 95 100 105 110 115 120 125 130 of the inner slot 12 to form a contour slot of the inner slot 12 to form a contour slot will now be seen. In initially assembling the parts the band will be inserted in the slot parts 12, 13 and 14. These slot parts have a combined length considerably greater than the transverse dimension of the clasp plate, and approximately equal to the transverse width of the band. Thereby the band may be formed in the shape of a trough or channel and pushed through the slots 12, 13, 14 to the desired position, according to the length which the article is to have. The twin lugs 15 occupy and interlock with the curved parts of the band, the lugs acting as spreaders, positioning the fabric during inserting and adjustment and securely locking and gripping it when adjusted. The band, with its edges thus folded or doubled in, may then be passed through the straight slot 10, the enlarged end portions 11 of which accommodate the doubled in fabric. When thus assembled a detachable or other form of binding piece 21 may be attached to the extreme end of the band.

This arrangement gives a combination in which the band is not only suitably accommodated and disposed, as described and shown, but which permits ready adjustment for length. Thus it is only necessary to pull the band through one of the slots to the desired extent, and take it up through the other slot, for the purpose of adjustment.

In all the forms shown it will be noted that the fabric by covering the exterior part 75 of the stud or socket avoids the possibility of the same catching in or injuring other materials, such as loose knit stockings, and at the same time prevents accidental opening of the fastener from such cause.

When the article shown in Fig. 2 is applied as a sock garter, the grip device 26 is attached to the sock in an ordinary way. Instead of having the grip piece 26 permanently attached by the extension 25 to the 85 pad 22 on which the stud 24 is mounted, the parts 25 and 26 may be separately constructed, so as to be applied over the stud 24 when the same are to be used, or detached therefrom when the article is to be used as 90 a band garter. This arrangement is not herein specifically shown as it is shown and described in connection with the convertible garter illustrated in my copending application Serial Number 736,362, filed September 6, 1924.

The embodiment shown in Figs. 5 and 6 introduces a further plan by which possible slippage of the band through the slots is minimized, although in most cases the contour of the slot 12 already described serves to give a gripping action on the fabric which effectively prevents slipping. In Fig. 5 the clasp plate 30 has an outer or straight slot 31 and an inner or bent slot 33 with extensions 34 and 35 analogous to Fig. 1. The stud however is not to be engaged directly with the plate 30, and the plate is formed with a slot 36 in which is engaged a spring socket member 37 into which the stud 24 may be snapped. The longitudinal slot 36 is shown as merging into the straight slot 31, and the double flanged socket piece 37 is slideable along the slot 36 by reason of the elongated character of the latter. Fig. 6 shows the clasp plate 30 mounted on one end of the band 19 and the stud 24 on the other end, the two mutually engaged. It will be seen that the pull on the two ends of the band, as indicated by the arrows, will cause the stud socket to be forced against the fabric passing through the slot 31, thereby effectively gripping or locking the fabric in slot 31 and preventing its slippage.

The form of clasp plate 40 shown in Fig. 7 is to illustrate that in either of the other embodiments the straight slot 10 or 31 may be shaped substantially symmetrically with the other slot 12 or 33. The figure shows a clasp plate having some of the features of Figs. 5

and 6, with the curved slot 33, 34, 35, but with the straight slot 31 replaced by a contour slot 41 having inwardly curved slot portions 42 at the ends.

5. In applying the garter, or other garment holder, the socket member or clasp plate 9 is manipulated to cause the stud hole 16 to pass over the head of stud 24, and then to cause the stud shank to pass into the stud slot 17, 10 where the tension holds it. Disengagement is readily effected by forcing the stud from the narrow slot and extracting it through the enlarged opening 16.

The slot 12 in Figs. 1-4 and the slot 33 in Figs. 5-7 may be specifically described as of the shape of the letter **C**, having the main slot portion, the offset slot portions, and the inturned ends, which however are not always necessary, although preferable with a 20 very wide band. The combined slots 12 and 16 in Figs. 1, etc., and the combined slots 41 and 36 in Fig. 7 may be described as **E**-shaped.

It will thus be seen that I have described 25 a garment holder, for example a garter, embodying the principles and attaining the advantages of the present invention. Since many matters of arrangement, design, proportion and detail may be variously modified without departing from the principles, it is not intended to limit the invention to such 30 matters except so far as set forth in the appended claims.

What is claimed is:

35 1. In combination, a wide band, and a narrow clasp plate formed with band receiving slots accommodating the band with its edges doubled in, one of the plate slots being formed with recurved portions at its ends 40 to shape and hold the doubled band margins flatly in position.

2. A garment holder comprising a band and two fastener members, one of said fastener members being a clasp plate narrower 45 than the band and formed with two band receiving slots arranged one at each end of the plate, each slot having its end portions formed to accommodate the excess fabric, the band having its side margins folded in 50 longitudinally upon itself and extending in folded condition through the two slots and longitudinally along the plate from slot to slot.

3. A garment holder comprising a band 55 and two fastener members, one of which is a clasp plate narrower than the band and

formed with band receiving slots arranged to accommodate the excess fabric, one or both of which slots is of the shape of the letter **C**, the band having its side margins 60 folded in upon itself and accommodated in such slots.

4. A garment holder comprising a band and two fastener members, one of which is a clasp plate narrower than the band and 65 formed with band receiving slots arranged to accommodate the excess fabric and wherein one or both band receiving slots is of a shape with a transverse main slot portion, and offset and inturned extensions arranged 70 to accommodate the total width of the band.

5. A garment holder comprising a band and two fastener members, one of which is a clasp plate narrower than the band and 75 formed with band receiving slots arranged to accommodate the excess fabric, and wherein one or both band receiving slots is of a shape to surround symmetrical lugs, which lugs occupy and grip the infolded fabric 80 edges.

6. A garment holder comprising a clasp plate in combination with a band wider than the plate, the plate formed with opposite band receiving slots shaped to receive the excess width of fabric in folded condition, 85 and a central stud receiving hole, so arranged that the band overlies, guards and protects the stud in said hole.

7. A garment holder comprising a clasp plate in combination with a band, the plate 90 formed with opposite band receiving slots, and a central stud receiving hole connecting with a band receiving slot.

8. A garment holder comprising a clasp plate in combination with a band, the plate 95 formed with opposite band receiving slots, a longitudinal slot merging into one of said slots, and a snap socket slidable in said longitudinal slot, whereby the pull on the band causes the socket to press the band in the 100 slot.

9. A garment holder comprising a clasp plate in combination with a band wider than the plate, the plate having band receiving 105 slots adapted to take the band with its margin folded in upon itself, at least one of said slots having a recurved shape, accommodating and holding the infolded margin.

In testimony whereof, I have affixed my signature hereto.

ROSSITER S. SCOTT.
